(57) CLAIM

The ornamental design for a Texas shaped scrub, as shown and described.

DESCRIPTION

FIG. 1 is a perspective view for a first embodiment of my design for a Texas shaped scrub;

FIG. 2 is a front view thereof;

FIG. 3 is a back view thereof;

FIG. 4 is a top view thereof;

FIG. 5 is a bottom view thereof;

FIG. 6 is a right side thereof;

FIG. 7 is a left side view thereof;

FIG. 8 is a perspective view for a second embodiment for a Texas shaped scrub; wherein the star-shaped hole penetrating through the front and back sides is shown in broken lines; and,

FIG. 9 is a front view of the second embodiment of the Texas shaped scrub, wherein the top, bottom, right, and left sides are identical to the views of FIGS. 4-7, respectively.

The broken lines are included for the purpose of showing portions of the Texas shaped scrub that form no part of the claimed design.
